UNITED STATES PATENT OFFICE.

EDWARD B. BIRKENBEUEL, OF PORTLAND, OREGON, ASSIGNOR TO COIN MACHINE MANUFACTURING COMPANY, OF PORTLAND, OREGON, A CORPORATION OF OREGON.

CHANGE-MAKING MACHINE.

1,116,375.

Specification of Letters Patent.

Patented Nov. 10, 1914.

Application filed August 8, 1912. Serial No. 714,085.

To all whom it may concern:

Be it known that I, EDWARD B. BIRKENBEUEL, a citizen of the United States, and resident of Portland, in the county of Multnomah and State of Oregon, have invented certain new and useful Improvements in Change-Making Machines; and I do hereby declare the following to be a full, clear, and exact description of the same, reference being had to the accompanying drawings, forming part of the specification, and to the figures and letters of reference marked thereon.

This invention relates to key controlled actuating mechanism and, while the invention may be utilized in key controlled shaft actuated mechanisms of various kinds, it is especially designed for use in a change making machine, specifically of the type illustrated in the application for patent filed by Thomas I. Potter on June 24, 1911, Serial No. 705,868, other types of machines of this general character being illustrated in the Ulmer Patent No. 1,020,466, and in the Potter Patent No. 1,011,845, to which patents reference may be had for a more complete understanding of the coin handling or discharging mechanism not fully illustrated herein.

The objects of the invention are to provide an exceedingly simple and highly efficient mechanism whereby the actuating shaft and parts actuated thereby may be coupled together and the uncoupling of the same controlled and the actuated parts locked by the keys or such keys as may have been operated in setting the machine.

Referring to the accompanying drawings, Figure 1 is a perspective view of parts of a change machine adapted for setting or positioning the selector, the supporting frame and bearings being largely omitted, and certain of the parts being broken away and in section. Fig. 2 is a sectional elevation of certain of the parts shown in Fig. 1 in the positions assumed by them when the actuated part has been positioned and locked. Fig. 3 is a similar view with the parts in normal position.

Like letters of reference in the several figures indicate the same parts.

The essential features of the machine may be briefly stated to be an actuating shaft such as A, an actuated mechanism which, in the machine illustrated, embodies prima-

rily a pair of segments B and C from which motion is communicated to other parts which will be hereinafter briefly referred to, a series of keys preferably arranged in sets or groups, and indicated by the reference letters D', D², D³ and E', E², E³, and a coupling mechanism which is adapted to couple the actuating shaft and actuated mechanism together, which coupling mechanism is disconnected and the actuated mechanism locked by coöperation with the keys.

In the preferred embodiment of the invention the actuating shaft A is provided with or adapted to move disks 12 conveniently rigidly mounted directly thereon and having concentric peripheral portions F, and recesses forming shoulders f and f'. Segments B and C are journaled on the shaft A, and each segment is provided with a pivoted dog 10 having a projection G adapted to enter the recess in the disk 12 and to co-operate with the shoulders f and f' so as to couple the actuating shaft and actuated mechanism together for simultaneous movement. Springs such as g are preferably employed for insuring engagement of the dog with the shoulders, as well as to insure the release of the dog from engagement with the keys as will be now explained. The keys D and E are preferably arranged in segmental series in a frame or key carrier H of ordinary construction, and with their inner ends in position to project when operated into the path of a projection G' on the dog, whereby when the dog advanced by the actuating shaft comes into contact with an operating key, as for example, the key D' in Figs. 1 and 2, it will be lifted out of its engagement with the disk 12, thereby disconnecting the actuating shaft from the actuated mechanism, and at the same time, the pivotal movement of the dog will move the projection G' up into the space between the operated key D' and the next preceding key as D', thereby securely locking the actuated mechanism against angular movement in either direction. When the projection G is lifted out of the recess and the disk 12 continues its movement, the projection G rides upon the concentric surface F of the disk, whereby the dog is held in engagement with the keys until the disk again returns to a position where the projection G may drop into the recess, whereupon the disk, dog and actuated mechanism will be re-

turned to normal positions by the return movement of the actuating shaft A.

The dog 10 is preferably provided with a projection G^2 at its rear end which will ride in contact with the concentric surface of the disk so as to limit the upward movement of the forward portion of the dog and serve as a means whereby the pivotal movement of the dog on the actuated mechanism may be controlled from the periphery of the disk independently of any other controlling means. The stems of the keys D' and E', etc., are preferably provided with coil spring 14, by which the keys are returned to normal position, and they are held in their operated position by a sliding plate K which engages teeth k on the stems of the keys, it being understood, of course, that when one key is depressed it will release any other previously operated key in the well understood manner. In accordance with the present invention, the release of previously operated keys is insured by the provision of a second incline 13 on each key stem above the tooth or projection k , which incline 13 is of greater height than the tooth or projection k and therefore when a key is operated and pressed downwardly below the position where it will be retained by the plate K, it will impart a greater longitudinal movement to the plate K than would the projection k , and thereby insure the release of previously operated keys.

In connection with this machine, it is desirable that the actuated mechanism shall be initially arrested if no key of the series controlling the same has been operated, and to accomplish this result there is provided what might be termed a "zero key". This zero key corresponds in construction to the keys D', E', etc., except that it has no finger piece and is made relatively short. Such a key is shown at L in the drawings and is adapted to be operated or set by the return of the dog 10 to normal position, shown in Fig. 3. When operated or set it projects into the path of the dog and will arrest the same during the initial forward movement, but the zero key will be released and withdrawn from the path of the dog by the operation of any other key of the series. In other words, the action of the zero key is in all respects similar to that of the other keys save that it is operated or set automatically. The means for operating the zero keys from the position shown in Figs. 1 and 2 to the position shown in Fig. 3 preferably consists of a vertically movable frame M adapted to overlie the ends of the keys L, as shown in Fig. 2. Said frame at its lower end is pivotally mounted on the upper arms of bell crank levers N, while the lower arms of said levers carry a bar N' located in position to be struck by the dogs 10 when they return to normal position, whereby the bell

crank levers will be rocked to draw the frame M downwardly, and with it the zero keys. During the final portion of the movement of the frame M, it is caused to ride out of engagement with the zero keys by the action of inclines or cam surfaces M' on the ends of the frame, which coöperate with projections or antifriction rollers M^2 on the fixed frame of the machine. Suitable springs such as m may be provided for moving the zero key actuating frame and bell crank from the position shown in Fig. 3 to that shown in Fig. 2.

In operation, the desired keys of the series are depressed and will be retained in operated position as explained. The shaft A is rotated forwardly by means of the crank handle A', carrying with it the segments B and C, constituting the first portion of the actuated mechanism. The dogs 10, coming in contact with the operated keys of the series of keys will be lifted out of engagement with the disks 12 on the shaft A and will simultaneously lock between the adjacent keys so that no further movement of the actuated mechanism in either direction can occur, until the shaft A and disk 12 turn to a position where the dogs may again drop into the recesses of the disk.

The actuated mechanism illustrated in Fig. 1 corresponds specifically to the mechanism of the application first above mentioned, and while it forms no portion of the present invention, specifically considered, it may briefly be described as a mechanism embodying a selector O adapted to be positioned in two directions, to wit: longitudinally and angularly, one of the segments, that lettered C being adapted to position the selector angularly, while the other of said segments B is adapted to position the same longitudinally. To transmit these motions to the selector it is mounted to slide longitudinally on its shaft O', but to rotate in unison therewith, and the shaft is provided with a pinion o meshing with teeth c on the segment C. A carriage P mounted to slide longitudinally on a guide p is adapted to coöperate with the selector O for moving it longitudinally of its shaft, and this carriage is connected by a flexible connection Q passing around an idler q , with the grooved periphery b of the segment B, whereby upon the rotation of the segment B the selector will be advanced along its shaft in proportion to the movement of the segment and the return longitudinal movement of the selector is effected by a return spring such as P' in Fig. 1. The periphery of the selector is suitably perforated or formed to control the movements of selector pins R which are advanced by a cam and roller R' , and said pins in turn through lever and arm connections, indicated at S in Fig. 1, control the ejectors for coins to be returned as

change in a money transaction. The provision of a single pivoted dog having oppositely disposed projections, one for directly engaging the disk on the actuating shaft and the other for directly engaging the stems of the keys dispensed with the employment of a complicated mechanism designed to accomplish the same results and at the same time secures an efficiency in operation never before attained. I do not wish to be understood, however, as limiting the invention to the particular form of the oppositely arranged projections for it is obvious that the upper projection may be variously formed for engagement with the operated key of the series and so as to effectually lock the dog and actuated mechanism against further movement in either direction when the connection or coupling between the actuated mechanism and shaft is released by withdrawing the lower projection from the recess in the disk.

Having thus described my invention, what I claim as new and desire to secure by Letters Patent of the United States is:

1. In a shaft actuated key controlled mechanism, the combination with the actuating shaft, a disk rigidly mounted thereon and having a concentric periphery and a recess, and a series of independently operable keys, of a segment journaled on the shaft, a dog pivotally carried by the segment and having a pair of spaced, inwardly extending projections, one relatively in front of the pivot and one relatively at the rear thereof, the projections extending toward the disk a distance sufficient for enabling both projections to ride in contact with the periphery of the disk at the same time and one of the projections being adapted at times to extend into the recess whereby the other projection is moved from contact with the disk, said dog having a projection extending toward the keys and disposed to move in a path into which said keys are designed to be projected when operated, whereby said last named projection is adapted to engage an operated key when the shaft is actuated for lifting the notch-engaging projection out of the notch and thus leaving the shaft free to move angularly independently of the segment.

2. In a shaft actuated key controlled mechanism, the combination with the actuating shaft, a disk rigidly mounted thereon and having a concentric periphery and a recess, and a series of independently operable keys, of a segment journaled on the shaft, a dog pivotally carried by the segment and having a pair of spaced, inwardly extending projections, the projections extending toward the disk a distance sufficient for enabling both projections to ride in contact with the periphery of the disk at the same time and one of the projections being adapted at times

to extend into the recess whereby the other projection is moved from contact with the disk, said dog having a projection extending toward the keys and disposed to move in a path into which said keys are designed to be projected when operated, whereby said last named projection is adapted to engage an operated key when the shaft is actuated for lifting the notch-engaging projection out of the notch and thus leaving the shaft free to move angularly independently of the segment.

3. In a shaft actuated key controlled mechanism, the combination with the actuating shaft, and a series of independently operable keys, of a segment journaled on the shaft, and means for transmitting movement from the shaft to the segment, said movement transmitting means being disposed to move in a path intersected by an actuated key, and said movement transmitting means being movable and adapted to be moved when brought into contact with an actuated key to a position between the actuated key and an adjacent non-actuated key for being locked against movement in either direction.

4. In a shaft actuated key controlled mechanism, the combination with the actuating shaft, disk mounted rigidly thereon and having a concentric periphery and recess in said periphery, and a series of independently operable keys, of a segment journaled on the actuating shaft in proximity to the disk, a dog pivotally mounted on the segment and having two oppositely arranged projections thereon, both movable in unison toward and from the shaft, one fitting the recess in the disk, and the other conforming to the space between adjacent keys of the series of keys, said last named projection being adapted to travel in a path intersecting the end of an operated key, whereby the dog will be released from its engagement with the disk and moved into locking engagement between adjacent keys.

5. In a mechanism such as described, the combination with a series of finger keys and a zero key, means for retaining said keys in operated position, an actuating shaft and an actuated mechanism with means for connecting the actuated mechanism and shaft controlled by the keys, of means for operating the zero key, when the actuated mechanism is returned to normal position, embodying a bell crank lever with which the actuated mechanism co-operates, a frame moved by said lever and co-operating with the zero key, and an incline for moving said frame out of engagement with the zero key.

6. In a mechanism such as described, the combination with the actuating shaft, disk on said shaft, having a recess therein, segment journaled on the shaft, pivoted dog

mounted on the segment and having a projection for coöperation with the recess, and a series of keys with which the dog is adapted to coöperate to effect its release from engagement in said recess, of a zero key, and means for operating said zero key embodying a bell crank lever with which the dog coöperates when returned to normal position, and a spring pressed frame

operated by said bell crank lever and overlying the zero key, and an incline and co-operating projection for moving said frame out of line with the zero key after the latter is moved to its operated position.

EDWARD B. BIRKENBEUEL.
